US00D909326S

(12) **United States Design Patent** (10) Patent No.: **US D909,326 S**
Yu et al. (45) Date of Patent: ** Feb. 2, 2021

(54) **MOBILE PHONE**

(71) Applicant: **Beijing Xiaomi Mobile Software Co., Ltd.**, Beijing (CN)
(72) Inventors: **Tao Yu**, Beijing (CN); **Gaochai Han**, Beijing (CN); **Yuwen Wang**, Beijing (CN)
(73) Assignee: **BEIJING XIAOMI MOBILE SOFTWARE CO., LTD.**, Beijing (CN)

(**) Term: **15 Years**

(21) Appl. No.: **29/685,573**

(22) Filed: **Mar. 29, 2019**

(30) **Foreign Application Priority Data**

Sep. 30, 2018 (CN) 2018 3 0557115
